INVENTOR
W. G. Ruggles

UNITED STATES PATENT OFFICE.

W. G. RUGGLES, OF WORCESTER, MASSACHUSETTS.

COOKING-RANGE.

Specification of Letters Patent No. 24,492, dated June 21, 1859.

To all whom it may concern:

Be it known that I, W. G. RUGGLES, of Worcester, in the county of Worcester and State of Massachusetts, have invented a new and Improved Cooking-Range; and I do hereby declare that the following is a full, clear, and exact description of the same, reference being had to the annexed drawings, making a part of this specification, in 10 which—

Figure 1, is a vertical section of my invention taken in the line x, x' , Fig. 2. Fig. 15 2, a vertical section of do, taken in the line y, y' , Fig. 1. Fig. 3, a horizontal section of do, taken in the line z, z' , Fig. 1. Fig. 4, a horizontal section of do, taken in the line x', x' , Fig. 1. Fig. 5, a horizontal section of do, taken in the line y', y' , Fig. 1. Fig. 6, a horizontal section of do taken in the line 20 z', z' , Fig. 1.

Similar letters of reference indicate corresponding parts in the several figures.

The invention relates to an improvement 25 on a cooking apparatus for which Letters Patent were granted to me bearing date May 18th 1858, and it is designed to carry out more perfectly in the present invention the principles involved and set forth in the former one.

To enable those skilled in the art to fully understand and construct my invention I will proceed to describe it.

A, represents the case of the range which may be of rectangular form. This case is 30 represented with single walls but it may have double walls and the space between filled with any suitable non-conducting substance to retain the heat. Within the case A, at one side, a fire chamber B, is placed. 35 This fire chamber may be encompassed with fire brick a , and a space C, is allowed back of the fire chamber and the back of the case A, which forms the lower part of the smoke stack or upright flue. At one side of the fire chamber B, an oven D, is formed, which 40 oven is provided with a central hollow shelf b , provided with a vertical partition plate c , as shown clearly in Fig. 5. This oven D, also has a bottom flue chamber d , provided 45 with a vertical plate e , as shown in Fig. 6, and both the fire chamber B, and oven D, are covered with a plate f , provided with the usual pot holes g , a chamber h , being formed under the part of said plate that 50 covers the oven, and a vertical partition plate i , placed therein. The chamber h ,

communicates with the fire chamber B, by means of a damper j , and the hollow shelf b communicates with the fire chamber by a damper k , both of which are shown in Figs. 60 1 and 2. The chamber h , shelf b , and chamber d , communicate with the upright flue C, by means of dampers l , see Figs. 4, 5 and 6.

E, is a damper by which a direct draft may be obtained with the upright flue C. 65

The oven D, and fire chamber B, have doors F, in front so that both may be completely inclosed within the case A. The space G, within the case A, above the fire chamber B, and oven D, may, when desired, 70 be employed for an oven. This space or oven G, has a horizontal central and hollow shelf m , placed within it, the interior of which shelf communicates with a vertical flue chamber n , at one side of the space or 75 oven G. The lower part of the flue chamber n , communicates with the fire chamber B, and a valve o , is placed within to cut off the communication when necessary,—see Fig. 1. The hollow shelf m , of the oven G, 80 has a horizontal partition plate fitted within it, so as to give it a circuitous flue route, the upper part or chamber formed by the partition plate communicates with the flue chamber n , and the lower part communicating 85 with a flue chamber n' , directly back of n . The lower part of the flue chamber n' , communicates with the upright flue C. The upper part of the flue chamber n , communicates with a chamber o' which has a vertical partition plate p , within it. The back part of 90 this chamber o' , communicates with an upright flue H, the lower end of which communicates with flue C. The oven G, is provided with doors I, so that it may be fully 95 inclosed. The shelf m , has a soap stone slab m' , placed on it which serves as a heat retainer. A similar slab may if desired be attached to the shelf b , of the oven D.

The operation is as follows:—If it is desired to cook by boiling only, the dampers k , E , o , are closed and the draft passes up through the chamber h , around the inner end of the partition plate i , and into the upright flue or smoke stack C, as shown by the 105 red arrows in Fig. 4. This arrangement it will be seen is precisely similar to an ordinary cook stove or range. In kindling the fire a direct draft is obtained by opening the damper E. In baking ordinary sized 110 articles such as may be contained within the oven D, the dampers j , k , and l , are opened,

o, and *E*, being closed and the draft or products of combustion pass through the chamber *h*, as before and also through the hollow shelf *b*, and chamber *d*, around the 5 ends of the partition plates *c*, *e*, into the flue or stack *C*. By this arrangement the oven *D*, will be thoroughly heated, the products of combustion passing over it, under it and through its center, as shown plainly in Fig. 10 1. In using the oven *D*, the holes *g*, may be occupied with pots and boiling or broiling and baking may be done simultaneously, but, in case the oven *G*, is to be used, boiling must be dispensed with, although the lower 15 oven *D*, may be used. In using the oven *G*, alone, the dampers *k*, *E*, are closed, and dampers *j*, *o*, opened. In the latter case the products of combustion pass through the chamber *h*, as usual and up the flue *n*, 20 through the hollow shelf *m*, and also through the chamber *o'*, the products of combustion in the latter case passing directly into flue or stack *H*, while the products of combustion that pass through the 25 hollow shaft *m*, enter the flue *n'*, and pass down into *C*. It will be seen therefore that the oven *G*, is heated precisely similar to oven *D*,—no heat is lost or wasted, the fuel being consumed and the heat generated 30 thereby applied in the most economical man-

ner. This arrangement of cooking range admits of an air-heating apparatus being applied in a very economical way, for the oven *G*, when not in use may be used as the air heating chamber, cold air pipes being 35 connected therewith, and hot air pipes leading therefrom. The shelves *m*, *b*, may be so arranged as to admit of being readily withdrawn, for the purpose of being cleaned, and also in case much space is required within 40 the ovens, and when articles are being boiled or broiled over the holes *g*, a communication may be allowed directly between the oven *G*, and stack *C*, or *H*, to allow the steam to escape therefrom into the stack, and thereby 45 prevent the odor from escaping into the room.

Having thus described my invention, I claim and desire to secure by Letters Patent:

The arrangement and combination of the 50 oven *D*, provided with a central hollow shelf (*b*), the oven *G*, provided with a hollow shelf (*m*), fire-chamber *B*, damper *E*, chambers (*h*, *d*) flues *C*, *H*, *n*, *n'*, substantially as and for the purposes herein shown and de- 55 scribed.

W. G. RUGGLES.
